HUMPHREY CALDER AND GEORGE BURGESS, OF RICHMOND, VIRGINIA.

Letters Patent No. 96,297, dated October 26, 1869.

IMPROVED SHOEMAKERS' LAST-HOLDER.

The Schedule referred to in these Letters Patent and making part of the same.

To all whom it may concern:

Be it known that we, HUMPHREY CALDER and GEORGE BURGESS, both of Richmond, in the county of Henrico, and State of Virginia, have invented a new and useful Last-Holder, or Work-Holder for Shoemakers; and we do hereby declare the following to be a full, clear, and exact description of the same, sufficient to enable those skilled in the art to which our invention appertains, to manufacture and use it, reference being had to the accompanying drawing, which is made part of this specification.

The object of our invention is to enable persons making boots or shoes by hand to either stand or sit at a bench, having their lasted work held in any of the positions necessary for sewing the inner and outer sole, pegging, and finishing the work, without the use of straps or attachment to the person.

Our invention consists of a strong and simple apparatus, of novel construction, adapted to hold the work in any desired position.

In the drawing—

Figure 1 represents a perspective view of the complete apparatus.

Figure 2, a longitudinal section of the same.

Similar marks of reference indicate like parts in the two figures.

A represents the base or bench, which may be of any desired form, constituting, if desired, the ordinary working-bench, having a seat for the workman, and the necessary receptacles for tools, &c.

B represents an adjustable pivoted stock, secured on the upper surface of the base A, by means of a clamp-screw, C, passing through a longitudinal slot, b, therein, or in other similar manner, and provided with a socket, b', for the reception of an adjoining member of the holder, and with a clamp-screw, D, by which to hold said member.

E represents a head or second stock, provided with a spindle, corresponding with the socket b' of B, in which it is held, and at its other end with the female member of an adjustable or locking ball-and-socket joint, consisting of a semi-spherical indentation, e', and a hinged portion or cover, E', having in it a zone or segment of the sphere e'', removed from the segment represented by the indentation e'.

The cover E' is hinged at one end to E, as shown, or in other suitable manner, and connected therewith, at its loose end, by means of a clamp-screw, F.

G represents an arm or stem, provided at one end with a ball, g, which is secured in the socket e' e'' of the head E, as shown, and at its other end with a screw or other suitable attachment for the lasts H, which are provided with corresponding sockets.

I represents a removable standard, secured by a suitable joint in the base A, and employed to support the fronts of the boots and shoes, when hammering or pegging them, being removed at other times.

The vamp or upper being secured on the last, in the usual manner, the last is secured on the end of the arm G, the clamp-screws C D F' loosened, and the work adjusted to the desired position, the loose joints b c b' e and e' e'' g permitting any required movement. The clamp-screws C D F are then tightened, and the work held in the position to which moved.

The joints b c and b' e, either or both, allow a longitudinal movement or extension, b' e, also a vertical swinging movement of the head E, and with it the arm G, and e' e'' g a rotation of the arm G around its longitudinal axis, and a limited oscillation around the centre of the ball g, in any desired direction.

The parts B F G have further a swinging movement in a horizontal plane on the clamp-screw C.

The movements permitted by the joints b' e and e'' g are the most essential, the latter providing the requisite universal adjustment, and the former enabling the necessary adjustment of the attaching-stem, including said universal adjusting-device, to adapt the holder for use in the different postures of the workman.

The arm G and standard I may be rendered capable of longitudinal extension, for vertical adjustment, to suit different heights of workmen, or different lengths of them may be employed for this purpose.

The means for longitudinal extension may in some cases be entirely dispensed with.

A ball-and-socket, or other universal joint, may take the place of the form of joint b' e, shown, if preferred.

The clamp-screws C D F may consist of studs and thumb-nuts, and D of a thumb-screw, as shown, or their equivalent, in either case may be employed.

The joint b' e may be employed for longitudinal adjustment, as shown, or only the slot b. In the former case the slot b may be dispensed with.

The base A, as a movable part, may be dispensed with, and the device secured to the floor of the room.

The several parts may be made of any suitable material, and their precise form and arrangement may be obviously varied.

Having thus described our invention,

We claim, and desire to secure by Letters Patent—

1. A last-attaching stem, G, having, in addition to

the movement permitted by an intermediate ball-and-socket adjusting-joint, $e' e'' g$, a rotary movement on a horizontal axis, e , to enable the holder to be adjusted, so as to be worked at either in a sitting or standing posture, substantially as herein described.

2. The combination, with the ball-and-socket adjusting-joint $e' e'' g$, of the joint $b' e$, adapted to permit independent horizontal adjustment, as described.

3. The combination, with the ball-and-socket adjusting-joint $e' e'' g$, of the joint $b' c$, adapted to permit separate horizontal adjustment, as described.

H. CALDER.
GEO. BURGESS.
